INVENTOR

H. E. Richmond,
BY Wm. A. McGrath,
ATTORNEY

UNITED STATES PATENT OFFICE.

HENRY E. RICHMOND, OF WESTWOOD, NEW JERSEY, ASSIGNOR TO UNDERWOOD AND UNDERWOOD, OF ARLINGTON, NEW JERSEY, A CORPORATION OF NEW JERSEY.

STEREOSCOPE.

1,157,419.

Specification of Letters Patent.

Patented Oct. 19, 1915.

Application filed May 14, 1914. Serial No. 838,434.

To all whom it may concern:

Be it known that I, HENRY E. RICHMOND, of Westwood, in the county of Bergen and State of New Jersey, have invented certain new and useful Improvements in Stereoscopes, of which the following is a full, clear, and exact description, such as will enable others skilled in the art to which it appertains to make and use the same.

10 This invention relates to improvements in hand stereoscopes, commonly called in the art "scopes."

Scopes as heretofore constructed generally consist of a wooden shaft, a hood connected to one end of the shaft, a lens frame within the hood, a septum connected to the hood between the lenses and extending longitudinally of the shaft, a picture holder slidably mounted on the shaft for focusing the picture and a handle pivoted to fold against the bottom of the hood or shaft. Scopes so constructed are bulky. Frequently the septum does not divide the picture perfectly, so that in focusing a part of one of the views extends over the other, or one of the views is cut off so that all of it will not be observed through the lenses and therefore a perfect picture is not in view of the user of the scope.

30 One of the objects of my invention is to provide a scope with the shaft and picture holder so constructed that they can be folded into the hood to make a compact scope, for packing or storing.

35 Another object is to provide means by which the lens frame may be moved backward and forward or adjusted within the hood so that the distance of the lens from the eye may be adjusted as the holder is moved toward or from the hood and the picture brought in perfect focus. The construction is such that the septum is also dispensed with.

40 Other objects will appear from the hereinafter description.

The invention will be fully understood from the following description taken in connection with the accompanying drawing.

50 Referring to the drawing, in which the same reference character indicates the same part in the several views: Figure 1 is a side view of the invention with the shaft and handle in their extended positions and the hood sectioned on line 1 of Fig. 3. Fig. 2, is

a view similar to that of Fig. 1 with the 55 shaft and picture holder collapsed into the hood and the handle folded against the bottom of the hood. Fig. 3, is a top plan view of the invention with the hood sectioned on line 3 of Fig. 1. Fig. 4, is a rear view 60 of the invention with the handle extended.

The part marked 20 on the drawing represents the hood which consists of the curved upper part 21 and the base 22, both being made preferably of light sheet metal, 65 such as aluminum. The rear edges 23 and 24 of the hood are curved to fit the face of the user. The lens frame 30 is provided with lenses 31 and 32. Each end of the lens frame is secured to the slide 33 or 34, which 70 is mounted inside of the hood and is movable longitudinally thereof. Pivoted to the base of the hood are the arms 35 and 36, the hood being depressed at 37 and 38 to receive the arms so that they will not extend 75 above the upper surface of the base. Pivoted to the free ends of these arms are the ends 40 and 41 of the "lazy tongs" 42 which form in the specific construction here shown, the extensible shaft. The lens frame is se- 80 cured to the shaft at 43.

44 is a picture holder which consists of the cross member 45 made of sheet metal, the upper edges 46 and 47 of which are over-turned to form ways or guides into which 85 slide the plates 48 and 49, the outer parts 51 and 52 of which are upturned and the ends 53 and 54 are outturned and these parts of the slides are slotted at 55 and 56 to receive the edges of the picture A. To 90 limit the outward movement of the plates 48 and 49 the same are provided with longitudinal slots 57 and 58 through which extend the rivets or pins 60 and 61. These rivets pivot to the under side of the picture 95 holder 44, the arms 62 and 63, to which the outer ends 65 and 66 of the lazy tongs are pivoted.

67 is a stop which consists of a plate se-cured to the under side of the picture holder 100 44 below the arms 62 and 63. This plate is provided with a longitudinal slot 68 into which projects one of the pins 69 connect-ing members of the lazy tongs. When this pin takes against the inner end of the slot, 105 the outward movement of the extensible shaft or lazy tongs is limited. To receive the heads of the pins or rivets 43, 69 and 70

pivoting the cross members of the lazy tongs together so that the members of the lazy tongs will lie flush against the top surface of the base of the hood, the base is depressed or struck downwardly at 71, which may be so deep that the handle 72 may be pivoted thereto or ears 73 may be secured by riveting or welding to the downwardly struck portion 71 and the handle pivoted to the ears as shown.

When the scope is constructed according to my invention, the picture holder and shaft may be folded to fit within the hood as shown in Fig. 2 and the handle folded 10 against the base of the hood so that the scope is compact and takes up little room for storing. When the scope is to be used, the shaft is extended and the slides or plates 48 and 49 are drawn out to receive the picture A as shown in Figs. 1 and 2. The picture holder can be moved toward or away from the hood, which movement adjusts the lens frame longitudinally within the hood and brings the lenses closer to or 15 farther away from the eye of the observer until the picture is adjusted to show a sharp and distinct view. By this construction the septum is dispensed with.

It is apparent that changes may be made 30 without departing from the spirit or scope of my invention. I have shown and described what I consider to be at the present time, the best embodiment of my invention. Other forms of shaft may be used for connecting and adjusting the lens frame and the picture holder and I may construct the part so that the lens frame and picture holder need not be moved or adjusted one relative to the other simultaneously.

40 What I claim as new and desire to obtain by Letters Patent, is:

1. In a stereoscope, a hood, a lens frame in said hood and means for adjusting the frame longitudinally of the hood.

45 2. In a stereoscope, a hood, a lens frame in the hood, slides mounted in the hood to move longitudinally thereof, the lens frame being connected to the slide and means for adjusting the frame.

50 3. In a stereoscope, a hood, a lens frame in the hood, a shaft, a picture holder on said shaft, said shaft being foldable within the hood.

4. In a stereoscope, a hood, a lens frame 55 in the hood, a shaft connected to the hood, a picture holder on said shaft, said holder and shaft being foldable within the hood.

5. In a stereoscope, a hood, a lens frame movable in the hood, a picture holder and 60 means between the frame and holder whereby the frame and the holder may be adjusted simultaneously.

6. In a stereoscope, a hood, a lens frame movable in the hood, a shaft connected to 65 the frame, a picture holder connected to the

shaft, the shaft being movable to bring the frame and holder toward or away from each other.

7. In a stereoscope, a hood, slides mounted in the hood, a lens frame connected to the slides, a collapsible shaft to which the frame is connected and a picture holder connected to the shaft.

8. In a stereoscope, a hood, a lens frame mounted in the hood to slide longitudinally 75 thereof, lazy tongs pivoted to the hood, means for connecting the lazy tongs to the frame and a picture holder connected to the tongs.

9. In a stereoscope, a hood, slides, mounted in the hood to move longitudinally thereof, lens frame connected to the slides, lazy tongs pivoted to the hood; means for connecting the lens frame to the lazy tongs and a picture holder connected to said tongs. 80

10. In a stereoscope, a hood, lazy tongs having one end thereof pivoted to the hood, a lens frame mounted in said hood to move longitudinally thereof, means for connecting the frame to the lazy tongs, a picture 85 holder having arms connected thereto, said arms being connected to the other end of the lazy tongs.

11. In a stereoscope, a hood, lazy tongs having one end pivoted to the hood, a lens 90 frame mounted in the hood to move longitudinally thereof and means for pivoting the frame to the lazy tongs, a picture holder having arms extending therefrom and connected to the other end of the lazy tongs and 100 a stop to limit the outward movement of the lazy tongs.

12. In a stereoscope, a hood, lazy tongs having one end thereof pivotedly connected to the hood, a lens frame mounted in the hood to move longitudinally thereof, said frame being pivotedly connected to the lazy tongs, a picture holder pivotedly connected to the other ends of the tongs, a plate secured to the picture holder, said plate having a longitudinal slot therein and a pin connected to the lazy tongs and extending into said slot. 105

13. In a stereoscope, a hood, arms pivotedly secured to the bottom of the hood, 110 lazy tongs, one end of the lazy tongs being connected to said arms, slides mounted to move longitudinally of the hood, a lens frame secured to the said slides, means for pivotedly connecting the lens frame to the lazy tongs, a picture holder having extensible members, pivoted arms secured to the picture frame, said arms being connected to the other end of the lazy tongs, a plate secured to the picture frame, said plate having a longitudinal slot therein and a pin secured to the lazy tongs and extending into said slot. 115

14. In a stereoscope, a picture holder consisting of a cross member, the edges of which 120

are overturned to form ways or guides, slides movable in said guides, each of said slides having an upturned and outturned end, slots in said upturned and outturned ends to receive a picture and means for limiting the movement of the slides in the ways.

In witness whereof I have hereunto set my

hand at the borough of Manhattan, city and State of New York this 6th day of May, 1914.

HENRY E. RICHMOND.

In presence of—

JOHN J. RANAGAN,
JOSEPH F. MOTT.
